UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

OPHTHALMIC MOUNTING.

1,324,176.

Specification of Letters Patent.

Patented Dec. 9, 1919.

Application filed April 17, 1919. Serial No. 290,770.

To all whom it may concern:

Be it known that I, WAYNE S. SEARLES, a citizen of the United States, and resident of Providence, in the county of Providence and State of Rhode Island, have invented certain new and useful Improvements in Ophthalmic Mountings, of which the following is a specification.

This invention relates to an improvement in ophthalmic mountings and more particularly to a non-metallic rim for a lens frame in such mountings, and the object of this invention is to provide such a rim of a continuous, annular band grooved internally 10 to fit over the lens frame and offset laterally from the plane of the rim to fit over or around the end pieces or other projections on the rim without being cut, notched or otherwise weakened.

It is found in practice where a non-metallic rim of xylonite or other similar material is cut or notched for the purpose of receiving or fitting around the end pieces that this cut-out portion so weakens 20 the stock that upon shrinking due to drying out, it is easily broken at the weakened portion. My improved rim obviates this difficulty as its cross sectional area is uniform and not reduced at any point in its circumference.

With these and other objects in view, the invention consists of certain novel features of construction, as will be more fully described, and particularly pointed out in the appended claims.

In the accompanying drawings:

Figure 1— is a front view showing my improved rims as applied to a pair of lens frames.

Fig. 2— is an edge view of the lens frames, showing my improved non-metallic rims applied thereto.

Fig. 3— is an edge view of a lens frame showing the end pieces in section and the rim portion bent or forced laterally from the plane of the rim sufficiently to pass around the end pieces without being cut away, notched or reduced in cross section at this point.

Fig. 4— is a front view showing a portion of a lens frame with the end piece connected thereto; also showing a portion of my non-metallic rim as applied to this lens frame, said rim being swaged or spread out slightly

beyond its normal periphery at the point 55 where it passes over the end piece.

Fig. 5— is an edge view showing the nose bridge member in section and showing the edge of the rim as swaged out laterally slightly beyond its normal plane so as to 60 pass over the arm of the bridge member without reducing the cross sectional area of the rim.

Referring to the drawings, 10 designates the usual metallic lens frame for eyeglass or 65 spectacle mountings, which frames are connected together by the usual nose piece 11 and the outer portions of these frames are usually split at 12 and the split ends are provided with end pieces 13 which extend 70 laterally outwardly therefrom and serve to perform two functions; first, to provide means whereby the frame may be bound about the lens and second, to provide a member 75 into which the temples 14 may be pivotally connected.

The primary object of this invention is to provide a rim 15 of shell, xylonite, celluloid, or other suitable material and to form this rim into a continuous, annular band internally grooved to receive and snap over each of the lens frames and instead of cutting or notching out the rim at the point where it passes over the end pieces I heat 80 this non-metallic rim at this point and mold 85 or press the same laterally and preferably forwardly as at 16, see Fig. 3, out of the normal plane of the rim bringing the side walls of the groove together as at 20 and molding this portion into a suitable shape 90 to fit smoothly and nicely over or around these end pieces 13 and that without reducing the stock of the rim in cross sectional area or in anywise weakening this rim at 95 this point so that it will retain its normal or maximum strength throughout the entire circle.

In some cases I also press the edge of the stock as at 17, see Fig. 4, outwardly beyond the normal periphery of the rim so as to 100 preserve the full cross sectional area and permit the stock to be a trifle thinner and wider at the point 16 where it passes over the end pieces.

Where the bridge member is connected by 105 arms 18 which extend rearwardly from the lens frame, instead of cutting away the stock of the non-metallic rim as is usually the

case, I simply swage or mold the edge rearwardly as at 19, see Fig. 5, so as to permit it to fit nicely over the arm member without reducing its cross-sectional area at this 5 point.

By my improved construction of rim I am enabled to make and sell these rims independently of the eyeglass mounting so that they may be readily applied to any 10 lens frame, as they will fit over the ordinary lens frame whose end pieces usually extend laterally therefrom.

A non-metallic rim of my improved construction has many advantages over the ordinary rim which is notched out to fit over the end pieces or bridge members; among others being that it may be applied to ordinary lens frames and snapped into position by the wearer; or may be applied by any 15 optician; second, non-metallic rims formed by my improved process of being offset to extend over or around the end pieces or other projections on the lens frame are very 20 much stronger and will stand much harder 25 usage than a rim which has been notched or weakened at this point.

The foregoing description is directed

solely toward the construction illustrated, but I desire it to be understood that I reserve the privilege of resorting to all the 30 mechanical changes to which the device is susceptible, the invention being defined and limited only by the terms of the appended claims.

I claim:

1. A non-metallic rim for a lens frame formed of a continuous annular band internally grooved to receive the lens frame, said rim at one point being offset laterally from the plane of the rest of the rim whereby 40 both side walls of said groove are caused to extend around a projecting member on the rim.
2. A non-metallic rim for a lens frame formed of a continuous, annular band internally grooved to receive the lens frame, the side walls of the grooved portion at one point in the frame being compressed together, and said compressed portion being offset laterally from the plane of the rim to 50 extend around the end piece on the frame.

In testimony whereof I affix my signature.

WAYNE S. SEARLES.
